Primary Examiner — Wan Laymon*(74) Attorney, Agent, or Firm* — Carter, DeLuca & Farrell LLP(57) **CLAIM**

The ornamental design for a ligation clip, as shown and described.

DESCRIPTION

FIG. 1 is a side perspective view of the ligation clip in accordance with an exemplary embodiment of the design; FIG. 2 is a right side view of the ligation clip shown in FIG. 1;

FIG. 3 is a bottom view of the ligation clip shown in FIG. 1;

FIG. 4 is a top view of the ligation clip shown in FIG. 1; FIG. 5 is a left side view of the ligation clip shown in FIG. 1;

FIG. 6 is a front view of the ligation clip shown in FIG. 1; and,

FIG. 7 is a rear view of the ligation clip shown in FIG. 1.
